UNITED STATES PATENT OFFICE.

GEORGE E. CURTISS, OF NEW BRITAIN, CONNECTICUT.

DESIGN FOR A TEA OR COFFEE POT.

44,521.

Specification for Design.

Patented Aug. 19, 1913.

Application filed June 11, 1913. Serial No. 773,132. Term of patent 7 years.

To all whom it may concern:

Be it known that I, GEORGE E. CURTISS, a citizen of the United States, and a resident of New Britain, in the county of Hartford, State of Connecticut, have invented a new, original, and ornamental Design for Tea or Coffee Pots, of which the following is a specification, reference being had to the accompanying drawings, forming part hereof.

The figure is a perspective view of a tea or coffee pot embodying my invention.

I claim:

The ornamental design for a tea or coffee pot as shown.

GEORGE E. CURTISS.

Witnesses:

H. R. BRYANT,
OSCAR A. MARSH.
